WILHELM A. SCHMIDT, OF ILION, NEW YORK, ASSIGNOR TO REMINGTON TYPEWRITER COMPANY, OF ILION, NEW YORK, A CORPORATION OF NEW YORK.

GRINDING MACHINE.

Application filed September 16, 1921. Serial No. 501,151.

My invention relates to machines for simultaneously grinding opposite faces of an article interposed between a pair of grinding wheels.

Generally stated, one of the main objects of the invention is to provide a highly efficient machine of the character specified.

More specifically stated, the objects of the invention may be said to be as follows:—

1st. To so mount the oppositely arranged grinding wheels that the axes thereof may be disposed out of alignment, and provide not only for grinding the article, but to enable the grinding wheels to be effectively dressed, one by the other.

2nd. The provision of an efficient work holder which has a freedom of movement in certain directions and is controlled or restrained in its movement in such direction by the direct action of the grinding faces of the wheels on the article supported by said holder.

3rd. The provision of efficient mounting means for the grinding wheels so that they may be moved relatively towards and away from one another and the grinding may be effected with great precision.

4th. The provision of efficient means for controlling the relative movements of the grinding wheels in the grinding and dressing operations.

5th. The provision of efficient and accurate gaging means for the wheels in both the grinding and dressing operations.

6th. The provision of comparatively simple, reliable and efficient automatically operating means for controlling the cycle of operations effected in grinding an article.

7th. The provision of single and effective means for bringing a supply of liquid to the grinding wheels.

8th. The provision of simple and effective means for preventing injury or breakage in the power transmitting means and assuring a proper and accurate grinding operation.

9th. The provision of an automatic control of the work holder without interfering with the floating character thereof.

10th. The provision of various details of construction which contribute to the production of an accurate and highly efficient grinding machine.

To the above and other ends which will hereinafter appear, my invention consists in

the features of construction, arrangements 55 of parts and combinations of devices set forth in the following specification and particularly pointed out in the appended claims.

In the accompanying drawings wherein like reference characters indicate corresponding parts in the various views.

Figure 1 is a fragmentary front elevation, with parts sectioned away, of one form of grinding machine embodying my invention.

Figure 2 is a fragmentary right-hand 65 elevation of the same with parts in section.

Figure 3 is a fore-and-aft vertical sectional view of the upper portion of the machine taken on the line 3—3 of Figure 1 and looking in the direction of the arrows at said 70 line.

Figure 4 is a corresponding detail sectional view of the lower portion of the machine with parts omitted, the view illustrating the cam and connections for the floating work 75 holder.

Figure 5 is a detail fragmentary vertical sectional view taken centrally through the right-hand spindle-carrying head on the line 5—5 of Fig. 2 and looking in the direction 80 of the arrow at said line.

Figure 6 is a fragmentary detail horizontal sectional view of the stop means for limiting the relative movement of the heads towards each other in the grinding operation, the 85 section being taken on the line 6—6 of Figure 1 and looking in the direction of the arrow at said line.

Figure 7 is a detail transverse sectional view of the grinding wheels showing the 90 manner of mounting the same on their respective spindles.

Figure 8 is a detail fragmentary fore-and-aft vertical sectional view showing the cam and connections for moving the right-hand 95 grinding wheel axially, the section being taken on the line 8—8 of Fig. 1 and looking in the direction of the arrow at said line.

Figure 9 is a fragmentary detail side elevation with parts broken away and showing 100 a portion of the work holder with an article clamped in place.

Figure 10 is a detail transverse sectional view of the same taken on the line 10—10 of Figure 9 and looking in the direction of the 105 arrow at said line.

Figure 11 is a detail transverse sectional view of the same taken on the line 11—11 of

Figure 9 and looking in the direction of the arrow at said line.

Figure 12 is a fragmentary detail vertical transverse sectional view, with parts omitted, of a portion of the work holder, the view being taken on the line 12—12 of Figure 3 and looking in the direction of the arrow at said line.

Figure 13 is a detail top plan view of the frame, which supports the floating work holding devices.

Figure 14 is a detail fragmentary rear elevation of one of the work holding devices with a type bar secured in place therein.

Figure 15 is a detail diagrammatic view looking endwise of the spindles of the grinding wheels and showing the relative disposition of the two oppositely disposed grinding wheels with the axes thereof out of alignment.

Figures 16 and 17 are diagrammatic front elevations of a work holding device with a type bar secured thereto, the views showing respectively, and very much exaggerated, different parallel and angular positions a work holding device and the type bar carried thereby may assume, as the parts are viewed from the front of the machine.

Figure 18 is a like view of the same showing different angular positions the parts may assume as viewed from above.

My invention is shown, in the present instance, embodied in a machine designed to simultaneously grind the opposite parallel flat bearing faces on the heel or pivot-end portion of a sheet metal type bar intended to be received in a bearing slot of a type bar segment of a typewriting machine. It should be understood, however, that the invention is not restricted to its embodiment in such a machine and that the machine shown may be employed wherever found available.

I contemplate embodying features of my invention in two forms of machines, one a so-called hand machine in which the various operations are controlled by hand, and the other a so-called automatic machine in which a complete cycle of operations in grinding a type bar is automatically effected.

I will first describe the automatic machine, and will then refer to the hand machine indicating wherein the automatically controlled parts of the first described machine are or may be arranged to be controlled by hand.

It should be borne in mind that in grinding opposite bearing faces of each type bar it is essential that the faces be ground in true parallelism to accurately co-act with the bearing walls of the slot in the segment in which the type bar is received and pivoted. It also is essential that the grinding at each side of the bar be only to a given depth so that the thickness of the bar

at this point will be reduced from, say, .035 of an inch to, say, .034 of an inch, and will properly fit within its guide slot and coact properly with the side walls thereof. With a consideration in mind of the great accuracy required in grinding the articles it will be understood how necessary it is to provide efficient means for mounting the grinding wheels and work holder and for controlling and gaging the movements thereof and for accurately bringing about an action of the grinding wheels on the work.

As shown in the present instance the machine may be said to comprise two oppositely disposed cup-shaped grinding wheels mounted on spindles or shafts arranged end to end and out of alignment, and movable axially relatively one to the other to effect a relative movement of the wheels towards and away from one another into and out of grinding position with reference to the article to be ground, and also into and out of co-action with each other to effect a dressing of the grinding faces of the two wheels one on the other. A floating work holder carries a type bar to be ground between opposing parallel faces of the grinding wheels and maintains it in such position during the grinding operations. However, the construction and mounting of the holder is such that the type bar has a freedom of movement axially of the shafts on which the wheels are mounted and at various angles to the shafts, and is controlled and restrained in such movements only by the direct contact of the article to be ground with the parallel grinding faces of the wheels. When, therefore, the wheels are brought towards each other the interposed floating type bar is automatically brought into proper parallelism with the faces of the grinding wheels by the direct action of said faces of the wheels themselves on the type bar, and the grinding action is properly applied and equally distributed in parallelism on both sides of the type bar. As will hereinafter appear, means are provided for controlling the movement of the work holder, with the work supported thereby, into and out of operative position, and for controlling the relative axial movements of the wheels into and out of grinding position, and for gaging the movements of the wheels against the work.

As shown in the present instance, the frame 1 of the machine which supports various working parts, has a bed 2 formed with longitudinally extending ways 3 on which spindle carrying heads 4 and 5 are mounted for adjustment towards and from each other. A screw 6 turns in a bearing in a bracket 7 secured by screws 8 to the right-hand end of the bed 2. The threaded portion of this screw is received in a tapped

opening in the head 4 and controls the adjustment of the latter along the ways 3. The adjustment of the left-hand head 5 is controlled in a like manner by a corresponding screw 10.

Referring particularly to Fig. 5, it will be seen that the driving spindle or shaft 11 of the right-hand grinding wheel 12 turns in adjustable bearings contained within a quill 10 or hollow supporting member 13 that is mounted for independent longitudinal movement in the right-hand supporting head 4 and constitutes an oil containing chamber in which the spindle turns. The head 4 carries two two-part surrounding supports for the quill 13, each comprising a section 14 held to its companion member 15 by screws 16. An oil chamber 17 is formed in each member 14, access being had thereto through an oil opening 18 ordinarily closed by a screw plug 20. The quill 13 is prevented from turning in its bearing in the head 4 by a spline 21 received in a spline groove 22 that enables the quill 13, nevertheless, to receive bodily longitudinal movement with the parts carried thereby independently of the supporting head 4. An oil opening that is normally closed by a screw 23 leads to the interior of the quill, and through this opening oil may be introduced to about one-half the height of the quill so that that portion of the spindle 11 contained in the quill may turn in a bath of oil. Suitable bearings 24 within the quill receive and support the spindle 11 and are provided with inclined outer surfaces surrounded by members 25 having corresponding co-acting inner inclined surfaces. An adjustable collar 26 has a threaded connection with a companion member 25 to effect an adjustment of the latter and thereby adjust the associated member 24. An end plate or head 27, centrally apertured for the passage of the spindle 11 therethrough, is secured to the right-hand end of the quill 13 by screws 28. An end plate or head 30 is secured by screws 31 to the left-hand end of the quill, and is provided with a thrust bearing 32 which co-acts with a flange 33 on the spindle. Contained within the quill 13, and loosely surrounding the spindle 11, is a flanged collar 34 that bears against a part 35 fixedly secured to the quill. A coiled expansion spring 36 surrounds the spindle and bears at one end against the flanged collar 34, and at its opposite end against a flanged collar 37 that loosely surrounds the spindle. The right-hand face of the collar 37 bears against anti-friction balls 38, which in turn bear against a flanged collar 40 that surrounds the spindle and is secured thereto by a screw 41. The balls 38 are received in a ball spacer 42 that is free on the shaft. The effect of this construction is to exert the force of the spring 36 through the anti-

friction balls against the spindle tending to force the latter longitudinally to the right in its bearings and to maintain the flange 33 on the spindle against the thrust bearing 32.

The inner end portion of the spindle 11 is, as best shown in Fig. 7, formed with a seat for a key 44 which connects a disk 45 to turn with the spindle. One side of the disk bears against the flange 33 on the shaft, whereas one side of the cup-shaped grinding wheel 12 bears against the opposite face of the disk. The spindle is slotted longitudinally at 46 to receive a spline projection 47 of a centrally apertured disk 48, to fixedly connect the latter to turn with the spindle. This disk 48 bears against the opposite side of the wheel 12 and is clamped in place by a disk 50 having a tapped central opening by which it may be screwed into place on the threaded end 51 of the spindle, and thus firmly hold the wheel 12 on its driving spindle. Rotation is transmitted to the right-hand grinding wheel 12 by a pulley 52 supported on the head 4 independently of the spindle 11 but operatively connected to the spindle so as to cause the latter to turn with the pulley but enable the spindle to move longitudinally with the quill 13 independently of the pulley. Thus the pulley 52 is mounted on bearing balls 53 through bearing members 54 on the pulley. Bearing members 55 on which the balls roll are supported on a flange supporting sleeve 56 secured to a bracket 57 on the head 4 by screws 58, screws 59 connecting the bracket 57 to the head. A centrally apertured end plate or disk 60 fits over the supporting sleeve 56, and has a projection 61 that is received in a longitudinally extending groove 62 in the bearing sleeve so as to prevent the plate 60 from turning on the supporting sleeve. A lock nut 63 is screwed onto the threaded end 64 of the supporting sleeve 56 and retains the pulley against removal therefrom. An oil opening 65 in the pulley, normally closed by a screw 66, communicates with the bearings of the pulley on its fixed support. A connecting member 67 is keyed to the outer reduced end portion of the spindle 11 and is held in place thereon by a nut 68. This member 67 comprises two arms that extend in opposite directions from the spindle and are received at the free ends thereof in grooves, ways or slots 70 formed in the inner walls of a cylindrical extension 71 on the pulley 52. This construction connects the spindle and pulley to turn together but enables the spindle to move axially independently of the pulley, and is in effect in the nature of a pin and slot connection between the two. It will be seen, moreover, that by this construction any strain exerted by the belt on the pulley 52 is resisted by the fixed bearing support on the head 4 and

is not transmitted to the spindle 11, or exerted thereon transversely of its axis.

From certain aspects of my invention any suitable means, whether hand actuated or automatically operating, may be employed to move the quill 13 and the parts carried thereby axially to move the grinding wheel 12 towards and away from its companion grinding wheel. In the present instance I have illustrated, as shown in Fig. 5, a sleeve 72 which is slit at 73 to form to a clamping member in the nature of a split ring or cylinder. This member surrounds the quill intermediate the two sets of supports 14 and 15 and is clamped tight on the quill by screws 74. These screws pass freely through openings in a flange 75 that projects rearwardly from the sleeve 72 above the split 73 therein, and engage in threaded openings in a corresponding flange 76 below the slit 73. The underside of the sleeve is formed with a recess in which is seated two bearing blocks 77 held in place by screws 78. These bearing blocks co-act with the upper rounded end of a crank arm 80 secured to a rock shaft 81 extending fore-and-aft from front to rear of the machine and mounted in bearings in the head 4. The forward end of this shaft is squared, as indicated at 82 in Figs. 1 and 2, to receive a hand manipulated crank (not shown), should it be desired to control the axial movement of the spindle 11 by hand. However, in the present instance I have provided means for automatically controlling the rock shaft 81, quill 13 and the axial movement of the spindle 11 and grinding wheel 12 carried thereby, as will hereinafter clearly appear.

It is unnecessary to move both of the grinding wheels axially towards and away from each other in order to obtain an effective grinding of opposite parallel faces of the article to be ground, or in order to dress the grinding faces of the wheels one by the other. Therefore, it is unnecessary to provide an axially movable quill for the spindle 83 of the left-hand grinding wheel 84, the latter remaining fixed against axial movement on its head 5. However, aside from the fact that the quill of the right-hand head 4 is movable axially, whereas the left-hand quill 13^a is held fixed on its head 5, and has no means connected therewith for moving it and the parts carried thereby axially, the bearings for both spindles and the driving connections with their pulleys, etc., are substantially identical. A detailed illustration and description of the mounting for the left-hand wheel would amount practically to a repetition of that already given, and it is therefore deemed unnecessary. Where corresponding parts are shown at both sides of the machine, they will be indicated by corresponding reference numerals.

There is one important point to be observed, however. As the machine is shown in the present instance, the two spindles 11 and 83 are arranged end to end but are maintained out of axial alignment, their axes being parallel and arranged one above the other, so that the grinding wheels 12 and 84 are eccentrically arranged with reference to each other, as indicated in Fig. 15. This arrangement is of importance in dressing, 75 truing or facing the wheels by their mutual action one on the other, as will be herein-after more fully brought out, but is unimportant so far as the grinding operation is concerned. For the latter purpose it is immaterial whether the spindles 11 and 83 are arranged end to end in alignment or are arranged with their axes parallel as shown. Therefore a machine may be so constructed that the axes of the spindles 11 and 83 are held in alignment for the grinding operation but may be shifted laterally relatively one to another to bring their axes in parallel arrangement and held in such arrangement during the truing or dressing operation. 80

The means shown in the present instance for automatically moving the rock shaft 81 and thus controlling the relative axial movements between the grinding wheels 12 and 84 comprises an angular lever, designated as a whole by the reference numeral 85 and best shown in Figs. 1 and 2. This lever is pivoted to turn freely on the rear end portion of the rock shaft 81 and is provided with a yoke-like depending arm 86 carrying oppositely disposed set screws 87 with lock nuts 88 thereon. Fixedly, though detachably secured to the rock shaft 81 is a hub 90 provided with a bifurcated extension 91 in which is fitted the upper end of a resilient 105 member or spring arm or plate 92 that is secured in place between the arms of the bifurcated extension by screws 93. The lower free end of this spring arm 92 extends down between the set screws 87. The construction is such that the only connection between said arm 86 and the rock shaft 81, by which motion is transmitted from the former to the latter, is through the set screws 87 bearing on the spring arm 92, 110 and the purpose of which will hereinafter more clearly appear. The horizontally disposed arm of the bell crank lever 85 is pivotally connected to a depending link 94. The lower end of this link 94 is in turn pivotally united to a rocking arm 95, as is best shown in Fig. 8. The arm 95 is pivoted at 96 to the frame 1 of the machine and has a forwardly projecting member or arm 97 which carries a laterally projecting anti-friction roller 98 at the free end thereof. This roller is received in a cam groove 100 in one side of a cam wheel 101 fixedly mounted on a cam shaft 102. The cam shaft 102 is mounted in suitable bearings in the frame of the machine 115 120 125 130

and extends transversely thereof beyond the right-hand side of the frame where a worm wheel 103 is secured thereto. The worm wheel meshes with a worm 104 on a shaft 105 mounted in bearings in a frame 106. This frame is pivoted at 107 (Fig. 2) to afford a bodily lateral movement of the worm shaft around the pivot 107 in order to throw the worm 104 into and out of mesh with the worm wheel 103. The rear end portion of the worm shaft 105 has a bevel gear 108 secured thereto and this gear meshes with a bevel gear 109 mounted on one end of a short shaft 110 which turns in a bearing supported by the pivoted frame 106. The inner end of the shaft 110 has a driving pulley 111 mounted thereon, as indicated in Fig. 1. A suitably driven belt 112 is received on and coacts with the pulley 111 to turn the cam shaft 102 through the intermediate train of gearing, and thereby effects a back and forth axial movement of the quill 13 and the parts carried thereby through the connection between the rock shaft 81 and the cam wheel 101.

Means are provided for automatically throwing the machine out of operation after it has completed a cycle of operations required to introduce a type bar in place, grind it and remove the ground bar. This involves the throwing out of operation of the cam shaft 102, so as to arrest the movements of the parts by which axial movements of the right-hand grinding wheel 12 is effected. In order to bring this about I have provided a cam 113 on the outer face of the worm wheel 103. This cam coacts with a roller 114 carried by an arm 115 secured to a rock shaft 116. This shaft is mounted in suitable bearings on the right-hand end of the frame 1 and carries a depending arm 117 provided at its lower end with an angular cut-out 118, as shown in Fig. 1, to receive an angular portion 120 at the forward end of the worm shaft 105. When the arm 117 is in the position shown in Figs. 1 and 2, the worm shaft will be supported in its elevated position, maintaining the worm 104 in engagement with the worm wheel 103 and rendering effective the operative connections from the pulley 111 to the quill 13 which carries the axially movable right-hand driving spindle 11. The hub of the arm 117 has an upwardly extending projection 121 which coacts with a plunger 122 pressed outwardly by a spring 123 contained within a guide sleeve 124 in which the plunger is received and works and which is fixed to the frame 1 of the machine. The force thus exerted by the spring 123 tends to maintain the arm 117 in a position where it will engage the shaft 105 and maintain the pivoted supporting frame elevated with the worm and worm wheel in mesh. When, however, the cam 113 reaches the roller 114, the lower end of the

arm 115 is moved to the right, thus rocking the shaft 116 and withdrawing the lower hook-like end portion of the arm 117 from beneath the shaft 105. The frame 106 is then free to turn around its pivot 107, lowering the worm 104 and disengaging it from the worm wheel, thus automatically disconnecting the operating means for the cam shaft 102 and arresting the axial movement of the right-hand grinding wheel.

The extent of this disengaging movement of the worm, through the pivotal movement of the frame 106, is limited and determined by a link 124 pivoted at its lower end, at 125, to the frame 106, and at its upper end, as at 126, to a lever 127 provided at its forward end with a handle 128 by which it may be controlled. This lever is pivoted to the frame of the machine at 130 and the downward movement at the rear end thereof is limited by a set screw 131 carried thereby and coacting with the stop pin 132, carried by frame 1. In order to reestablish the driving connection between the worm shaft 105 and the cam shaft 102, it is merely necessary to depress the handle 128, thereby turning the frame 106 on its pivot 107 and elevating the worm 104 into mesh with its worm wheel 103. At this time the hook-like lower end of the arm 117 will engage beneath the forward end of the worm shaft and lock it in its elevated position until a complete cycle of operations has taken place, when the cam 113 will again be effective to automatically disengage the arm 117 and enable the worm to be disengaged from the worm wheel, and an arrest of the cam shaft to be effected.

I provide means for limiting the axial movement of the right-hand grinding wheel 12 into grinding relation with the type bar and towards the wheel 84, and thus accurately determine the depth of the grinding operation and the thickness to which the article is ground. For this purpose I provide gage or stop devices which are best shown in Figs. 1, 2 and 6. The devices in question comprise a so-called interponent or stop 133 that corresponds in thickness to the thickness of the article after the grinding operation has been effected. This interponent in the present instance is shown mounted on a supporting member 134. The member 134 has a cylindrical stem 135 seated in a bearing 136 on the head 4 to turn on a horizontal axis, so that the interponent 133 in turning with the member 134 may be shifted into or out of operative position. A thumb screw 137 is seated in a tapped opening in the bearing 136 and is adapted to bear at its end against the cylindrical stem 135 and hold the device 134 in either its operative or inoperative position, as desired. When the device 134 is turned down to operative position, illustrated in Figs. 130

1 and 2, the part 133 will be interposed between two stop members 138 and 140. Referring more particularly to Fig. 6, it will be seen that the stop member 138 has a reduced end portion 141 by which it may be detachably seated in an opening 142 in the head 4, whereas the stop 140 is formed as the inner end of a micrometer screw 143 received in tapped openings in forwardly projecting flanges 144 and 145 of the member 72 which is secured to the quill 13. The head of the micrometer screw is provided with indices, as indicated at 146, for cooperation with a relatively fixed pointer 147, whereas a lock nut 148 secures the screw and its stop 140 in adjusted position. When the device 134 is in the operative position, with its member 133 interposed between the stops 138 and 140, the extent of movement of the quill 13, with the parts carried thereby, will be limited in the approach of the grinding wheel 12 towards its companion grinding wheel 84, thus determining the extent or depth of the grinding operation, which may be varied by an adjustment of the micrometer screw 143. It has hereinbefore been pointed out that the axial movement of the right-hand grinding wheel 12 is transmitted through the resilient member 92, and it should be understood that the parts are so adjusted, constructed and arranged that prior to the arrest of the axial movement of the grinding wheel 12 by the stops 133, 138 and 140, the resilient member 92 will be flexed, exerting its force to hold the stops in contact and to press the grinding face of the wheel 12 against the article to be ground. It will thus be understood that when the stops 133, 138 and 140 coact to arrest the axial movement of the right-hand driving wheel 12, the force of the positively actuated connections from the cam 101 is exerted through the resilient member 92, and there is an assurance of the proper extent of axial movement of the wheel, without at the same time there being any liability of injuring the construction, or the lack of proper extent of movement due to wear on the parts or looseness in the connections, etc. When it is desired to dress or face the wheels one by another, it is merely necessary to turn the member 34 out of operative position where its part 133 is interposed between the stops 138 and 140, thus enabling the grinding faces α of the wheels to be brought into contact with each other. The stops 138 and 140 at this time limit the axial movement of the wheel 12 towards the wheel 84, but an adjustment of the stop 140 enables the extent of this movement to be varied at will.

By arranging the axes of the wheels out of alignment in the manner shown and described, it will be understood that every point on the grinding face α of the wheel

12 will cut crosswise at every point on the grinding face α of the wheel 84, and vice versa, as will be clearly understood from a consideration of Fig. 15. It is therefore possible to effectively dress the grinding faces of the wheels one by another, and to dress or true the faces of the wheels accurately and in parallelism.

I will now describe the floating work holder by which the articles to be ground may be automatically interposed between the grinding wheels; may be moved back and forth during grinding operation; and may be removed from between the grinding wheels after the article is ground.

Referring more particularly to Figs. 1, 2 and 3 and 9 to 14, inclusive, it will be seen that a type bar A, or other article to be ground, is adapted to be seated in a grooved seat 149 in one side of a work holding device 150. The article is clamped in place in its seat by a clamp or contact device 151 fixed by its hub to a cylindrical stem 152 which is adapted to slide lengthwise in a bearing 153 in the member 150 as the contact device 151 moves into and out of clamping engagement with the article to be ground. The hub of the clamp is also mounted to slide in a bearing 153^a in the holding device. The stem 152 projects through to a point at the opposite side of the device 150, and at its end portion is formed rectangular in cross-section, as indicated at 154. This rectangular end portion extends through a corresponding opening in a bowed or arched spring 155 formed as indicated in Figs. 10 and 14, so that the central portion of the spring is flat while the free end portions thereof are bent so as to bear against one side of the work holding device 150. A pin 155^a projecting from a side of the holding device passes through an opening in the spring 155 and prevents it and the clamping member from turning. A hand actuated controlling member 156 is pivoted at 157 to the rectangular portion of the stem, the free end of the controlling member 156 constituting a finger piece by which it may be moved on its pivot 157 from the full to the dotted line position indicated in Fig. 14, or vice versa. The controlling member 156 is in the nature of a lever formed with a cam or enlargement 158. It will be seen that the distance from the pivot 157 to the flat end portion 160 of the controlling member is considerably less than the distance from said pivot 157 to the flat face 161 of said member. In consequence of this, a movement of the controlling member from the dotted to the full line position in Fig. 14, is effective to flex the spring 155 and cause the force of the spring to be exerted longitudinally of the stem 152, and to be applied through the contact 151 to the type bar, in order to clamp the latter in place in its seat. It will be understood moreover,

that when the flat face 161 of the controlling member engages the spring as shown in full lines said controlling member and the parts controlled thereby will be locked or maintained in the position shown, to clamp the type bar to the holder under the force of the spring 155. When, however, the controlling member 156 is turned to the dotted line position the force of the spring 155 on the 10 clamp is released, enabling the latter to be shifted longitudinally of its stem 152 to release the type bar and permit its removal from the holder. If desired suitable auxiliary means may be employed to aid in properly positioning and holding the type bar in place on the holder, such means for example as a sheet metal bracket 162 secured to the upper edge of the holder by screws 163 and adapted to engage in a recess 164 formed 20 in the type bar.

In the present instance I employ two of these work holders 150 constructed and mounted alike and the description of one applies to the other. Each work holder 150 25 is provided with a depending stem, support or carrier 165 by which it may be mounted to receive a pivotal movement around a substantially vertical axis when a type bar is in the operative position shown 30 in Fig. 3. Thus, upstanding coned pivots 166 connect each work holding device 150—165 to an arm, support or carrier 167, whereas stops 168 on opposite sides of each member 165 coact with stop faces 170 on 35 the associated arm 167 to limit the rotative movement of the member 150—165 around its pivots 166. This movement of each work holding device 150—165 around the pivots 166 I have attempted to illustrate in Fig. 18. 40 This view is intended to represent the parts as they are seen when viewed from above the work holding device, although the extent of movement is shown greatly exaggerated in order to clearly indicate that by this angular movement the plane of the heel *b* of the type bar to be ground may assume different angles relatively to the axes of the grinding wheels, for purposes which will hereinafter more clearly appear. Each supporting arm 167 is supported by pivots 171, 45 the axes of which are at right angles to the axes of the pivots 166 and connect the arm 167 to a depending link, support or carrier 172 supported by pivots 173, the axes 50 of which are parallel with the axes of the pivots 171. The pivots 173 connect the link 172 with an arm or support, or carrier 174 of a frame, or head designated as a whole by the reference numeral 175 and pivoted 55 on a spindle 176 to an upright primary or main support, or carrying arm 177, which may, if desired, be provided with a handle 178. It will be observed that the supporting frame or head 175 is provided with 60 two arms 174 arranged at right angles to

each other, as indicated in Fig. 13, and each arm supports a link 172, an arm 167, and a work holding device 150—165. Each arm 174 is provided with a depending lug or stop 179 (see Figs. 3 and 12) that is received between two lugs or stops 180 on the associated link 172. The lower end of each link is likewise provided with two lugs or stops 181 between which is received a stop or lug 182 which projects upwardly from the associated arm 167. The stops 179 and 180 limit the pivotal movement of the associated link 172 around its pivots 173, whereas the lugs or stops 181 and 182 limit the pivotal movement of the arm 167 around the pivots 171 which connect said arm with its link 172. This manner of pivoting a work holding device on a supporting arm 174 enables said device to assume the different positions to bring the heel of the type bar into different parallel planes which I have attempted to represent in Fig. 16. In this figure the parts appear as seen from the front of the machine although it will be understood that the diagrammatic showing represented greatly exaggerates the extent of movements permitted. In Fig. 17 the diagrammatic showing is intended to represent the movement of a work holder around its supporting arm 174 on the pivots 173, or on the pivots 173 and 171 to such a position as to present the heel of the type bar at different angles with reference to the parallel grinding faces of the grinding wheels. This view represents the parts as they would appear when seen from the front of the machine, although it will be understood that, as in Figs. 16 and 18, the extent of movement is greatly exaggerated in order to more clearly represent the character of movement of the floating work holder.

The supporting frame 175 has its hub notched at two points at 90° apart, as indicated at 183. Each of these notches is adapted to receive the engaging nose of a latch 184 pivoted at 185 in bearings on the upright arm 177 which supports the frame 175. A plunger 186 is received in a guide opening 187 in a part of the arm 177 and is pressed forwardly by an expansion spring 188 to cause the engaging nose of the latch to lock the carrier or supporting frame 175 against turning movement on its pivotal support or spindle 176. A finger piece 190 facilitates a disconnection of the latch to enable the frame to be given a quarter turn on its pivot 176 to move one work holding device to a position where a ground type bar may be readily detached therefrom, at the same time bringing a newly introduced bar to be ground, and which is carried by the other work holding device, to a position where it may be inserted between the grinding faces of the wheels 12 and 84. In short the pivotal movement of the frame or

head 175 on the arm 177 enables one holder to replace another in position for use.

The supporting arm 177 is provided with hubs 191 by which it is supported on a horizontal rock shaft 192 arranged parallel with the driving spindles 11 and 83, the shaft 192 being supported in suitable bearings on the frame of the machine. An arm 193 has a split hub held together by a screw 193^a and by means of which the hub is clamped to the shaft 192 to fixedly connect the arm 193 to the rock shaft. Said arm 193 in turn is connected by a pin 194 and a screw 195 to the arm 177 to cause the latter to turn with the arm 193 and the rock shaft 192.

Referring more particularly to Fig. 4, it will be seen that a crank arm 196 is mounted by its hub 197 on the rock shaft 192 and is fixedly connected thereto by a screw 198. This arm extends rearwardly and carries a laterally projecting anti-friction roller 200 which is received in a cam slot 201 in a cam wheel 202 secured to the cam shaft 102. In this manner the pivotal movement of the arm 177 and the parts carried thereby is automatically controlled by the cam 202. The character of the cam is such that a loaded work holder is first moved rearwardly to introduce the heel *b* of the type bar between the grinding faces of the wheels, as represented in Fig. 3. Then the type bar receives a slight movement fore and aft of the machine during the grinding operation. After the grinding operation is completed the arm 177 is moved forwardly to the limit of its motion in order to withdraw the ground type bar from between the grinding wheels. The operator may then release the latch 184, give the frame 175 a quarter turn to bring the other loaded work holding device in position to introduce its type bar between the wheels; this movement of the frame 175 carrying the work holder with the ground bar to one side where the latter may be readily removed and another type bar to be ground may be introduced in its place.

I have hereinbefore pointed out that the cam shaft 102, by which the fore and aft rocking movement of the arm 177 is effected, also automatically controls the axial movement of the right-hand grinding wheel into and out of grinding position. I also have pointed out that this cam shaft is controlled by the worm shaft 105 which automatically brings about an arrest of the cam shaft through an automatic disconnection of the worm 104 from its worm wheel 103 after a cycle of operations has been completed. This cycle of operations is started by a depression of the handle 128 to connect the worm and worm wheel, and consists in first automatically moving the arm 177 to introduce a type bar into position between the

two grinding wheels; then automatically moving the right-hand grinding wheel 12 against the heel of the type bar to automatically position the floating type bar with the opposite sides thereof in parallelism with the grinding faces of the wheels and effect a grinding operation; a fore and aft movement of the arm 177 being effected during this grinding of the type bar. After the type bar has been ground the grinding wheel 12 is automatically moved to the right out of grinding position and the arm 177 is automatically given a movement forward to withdraw the ground type bar from between the wheels. This completes the cycle of operations and at this time the cam 113 actuates the arm 115 to release the lower end of the arm 117 from beneath the worm shaft and permit an automatic disengagement of the worm 104 from worm wheel 103, thus effecting an arrest of the cam shaft and the parts controlled thereby, although the grinding wheels may be continuously driven from their pulleys 52.

From the foregoing description it will be understood that the heel of each floating type bar when introduced between the grinding wheels is free to receive a limited extent of lateral movement, or movement longitudinally of the axes of the grinding wheels in parallel planes as indicated in Fig. 16, or to assume different angular positions with reference to the axes of the wheels for a limited extent as indicated in Figs. 17 and 18, although the type bar is held firmly in position against movement with the grinding wheels in the direction of their turning movements. This limited lateral movement of each work holder with its type bar enables the type bar to be ground to automatically accommodate itself to the grinding faces of the wheels and accurately find its proper position in parallelism therewith as the bar is pressed by and between the wheels. It follows therefore that each article is accurately ground on opposite faces in parallelism between the opposing faces of the grinding wheels which alone restrain the lateral movements of the article, and that the positioning of the article to be ground, and the maintenance thereof in parallelism with the faces of the wheels, is determined wholly by the direct contact of the grinding faces of the wheels on the article to be ground. Otherwise stated the floating character of each holder in operative position leaves the type bar unrestrained for limited extent of lateral movement except for the direct contact of the grinding faces of the oppositely disposed grinding wheels therewith, and thus enables each type bar to properly position itself automatically as the wheels are moved relatively towards each other into contact with the bar, and bring the sides of the latter in accurate parallelism with the

faces of the wheels by the direct contact of the latter with those surfaces of the type bar that are to be ground.

I prefer to provide a longitudinal opening 5 extending entirely through one of the spindles 11 or 83 by which the associated grinding wheel is turned in order to supply water or liquid to the interior of the cup shaped grinding wheels 12 and 84. In Fig. 10 5 I have shown such an opening 203 extending entirely through the spindle 11. In practice, however, I prefer to employ a corresponding opening 204 through the left-hand spindle 83 and to connect said opening by means of a pipe 204^a (see Fig. 1) 15 with a suitable source of supply by which liquid may be fed to the inner sides of the wheels. If desired a suitable valve 205 may be employed to control the flow of liquid 20 from the source of supply. Such valve may be automatically controlled from a cam 206 on the cam shaft 102.

I may also provide suitable means for receiving liquid from the wheels and carrying 25 it to a suitable point of discharge. In Fig. 3, I have shown a sheet metal trough 207 carried by the arm 177 and disposed opposite the space between the grinding wheels. This trough is adapted to discharge into a 30 sheet metal trough 208 carried by the lower section 209 of a two-part housing for the grinding wheels, or to discharge directly into a trough 210 formed in said lower section. The liquid may be conveyed from the 35 trough 210 through the housing to an outlet 211 therein and thence to a suitable point of discharge. The housing for the grinding wheels is separate and distinct from the supporting heads 4 and 5 and is mounted on 40 the ways 3 of the bed 2. In addition to the lower section 209 the housing comprises an upper section or cover 212 arranged over the wheels and pivoted at 213 to the lower section 209, so that the forward end of the 45 upper section may be swung up and rearwardly to give access to the grinding wheels. It will be seen that this section 212 is apertured at 214 whereas the lower section has a corresponding opening 215 (Fig. 1) to receive 50 a work holder and permit the heel of the type bar to be received between the oppositely disposed grinding wheels. Suitable means may be provided to secure the upper section 212 in place. Referring particularly 55 to Figs. 1 and 3 it will be seen that for this purpose I provide a link 216 pivoted at its lower end, as at 217, in a slot in the lower section 209 of the housing and threaded at its upper end to receive a thumb nut 218. 60 This link may be turned on its pivot into a registering slot on the forwardly extending flange 219 of the upper section. When thus positioned, and the thumb nut 218 is turned down against the flange 219, the upper section 65 of the housing will be firmly held in

place on its lower section. A backing up of the thumb nut enables the link to be turned forward to release the cover section of the housing.

A sheet metal cover plate 220 may be secured to each of the heads 4 and 5 over the quill 13 or 13^a. 70

When a hand controlled machine is to be provided, the cam shaft 102, the connections between said shaft and the parts controlled thereby, the worm wheel 103, and the various parts associated therewith are omitted. The arm 177 may then be provided with suitable stop devices 221, 222 and 223 to limit the movements of the arm 177 both forwardly 80 and back, and the handle 178 may be employed to effect such movements of the arm. The axial movements of the grinding wheel 12 is brought about by a hand actuated crank (not shown) applied directly to the squared 85 end 82 of the rock shaft 81. Otherwise the construction and operation of the hand controlled machine is the same as that previously described.

Suitable means, not shown, are provided 90 for controlling the driving belts of the pulleys 52 to turn the grinding wheels in opposite directions in their grinding operation, and to reduce the speed of the grinding wheels when they are brought into contact 95 with each other to dress the faces of the wheels by their mutual action one on the other.

From what has been said it will be understood that a work holder 150 cannot move 100 lengthwise of the main carrying arm or primary support 177, and when in use is controlled and restrained in its movements toward and from the axes of the grinding wheels and in the direction of rotation of 105 the wheels, but is supported to move a limited distance free from restraint in every other direction, so that the direct contact of the parallel grinding faces of the wheels with the article carried by the holder causes 110 the article to accommodate itself to said faces and assume a position in parallelism therewith, and receive an equal and true grinding on both sides between the wheels.

It also will be understood that the construction is such that the grinding wheels 115 are maintained against deviation from the true course in which they should turn and be fed axially one relatively to another; that when occasion requires the grinding faces of 120 the wheels may be expeditiously dressed one by another without the necessity of dismounting any part of the machine or altering or destroying any adjustment of the parts required in grinding the type bars; it 125 being merely necessary to shift the member 133 out of operative position; that if any adjustment of the micrometer screw 143 is required in dressing the wheels it may ordinarily remain in such adjusted position after 130

the dressing operation for effective use in grinding, or, if conditions demand, may be adjusted as required.

Various changes may be made without departing from the spirit of my invention, and certain features thereof may be employed without others.

What I claim as new and desire to secure by Letters Patent, is,

10. 1. In a combined grinding and dressing machine, the combination of two grinding wheels operative to grind parallel faces on opposite side of the article to be ground, means for mounting said wheels to turn on unvarying parallel axes, and automatically operating means for effecting a relative axial sliding movement between said wheels into and out of grinding relation with the article and when desired to bring the grinding wheels eccentrically arranged one with reference to the other into contact to dress one wheel by the other.
20. 2. In a combined grinding and dressing machine, the combination of two cup-like grinding wheels the grinding face of each of which is in a plane at substantially right angles to its axis of rotation and by which opposite parallel faces are ground on the interposed article, means for mounting said wheels to turn on parallel axes, and automatically operating means for effecting a relative axial sliding movement between said wheels into and out of grinding relation with the article and when desired to bring the grinding wheels eccentrically arranged one with reference to the other into contact to dress one wheel by the other.
30. 3. In a combined grinding and dressing machine, the combination of two grinding wheels that turn on unvarying axes and have a relative movement in the direction of the axes on which they turn to exert pressure against and act on the interposed article to be ground, means for supporting said wheels so that the grinding face of one wheel crosses transversely the grinding face of the other wheel, and means whereby said wheels may be brought into contact to dress one by the other.
40. 4. In a grinding machine, the combination of two grinding wheels having parallel grinding faces adapted to be moved relatively one to the other and to simultaneously grind opposite parallel faces on the interposed article to be ground, a floating holder to which the article may be secured and by which it may be brought and maintained between oppositely disposed parallel grinding faces on said wheels, and means for mounting said holder so that it has a controlled movement towards and from the axes of said wheels and also a limited uncontrolled movement between opposing faces of said wheels and longitudinally of said axes and at different angles thereto but is

restrained against turning movement with said wheels.

5. In a grinding machine, the combination of two grinding wheels adapted to be moved relatively one to the other and to simultaneously grind opposite faces of the interposed article to be ground, a floating holder to which the article may be secured and by which it may be brought and maintained between oppositely disposed grinding faces on said wheels, and means for mounting said holder to turn on axes at substantially right angles one to another so that the article may be held restrained against movement between said wheels in certain directions but has limited uncontrolled movements between said wheels in other directions.

6. In a grinding machine, the combination of two grinding wheels having oppositely disposed parallel grinding faces by which an interposed article may be ground simultaneously on opposite parallel sides, a holder to which the article may be secured and by which the article may be introduced and maintained between the parallel grinding faces of said wheels, and means for supporting said holder so that it has a limited freedom of movement in certain directions controlled or restrained only by the parallel grinding faces of the wheels on the article, thus enabling the article to automatically find its position between and parallel to the grinding faces wholly by the pressure of the grinding faces thereon.

7. In a grinding machine, the combination of two grinding wheels having oppositely disposed parallel grinding faces by which an interposed article may be ground simultaneously on opposite parallel sides, a holder to which the article may be secured, and means by which said holder may be shifted to introduce and maintain the article to be ground between the parallel grinding faces of said wheels and which enable the holder to receive a limited unrestrained movement between said wheels to bring the parallel sides of the article to various planes parallel to the grinding faces of both of said wheels and also to planes at various angles thereto but which restrains the holder and article against movements in said planes.

8. In a combined grinding and dressing machine, the combination of two spindles arranged end to end but out of axial alignment, a grinding wheel carried by each spindle and between which the article may be received and ground by said wheels arranged one eccentrically of the other, and a hollow oil containing bearing member supporting one of said spindles in a bath of oil and mounted for axial sliding movement with its spindle towards and away from the spindle of the other wheel to move the wheels together in grinding relation one

against the other or separate them, whereby the wheels may be dressed one by the other.

9. In a combined grinding and dressing machine, the combination of two spindles arranged end to end but out of axial alignment, a grinding wheel carried by each spindle and between which the article may be received and ground by said wheels arranged one eccentrically of the other, a bed, a head adjustable along said bed, and a bearing member supporting one of said spindles and mounted for axial sliding movement with its spindle on said head towards and away from the spindle of the other wheel to move the wheels together into grinding relation with the interposed article to be ground or separate the wheels, and also to enable the wheels to bear one against the other to dress them one on the other.

10. In a combined grinding and dressing machine, the combination of two spindles arranged end to end but out of axial alignment, a grinding wheel carried by each spindle and between which the article may be received and ground by said wheels arranged one eccentrically of the other, a bed, a head adjustable along said bed, a bearing member supporting one of said spindles and mounted for axial sliding movement with its spindle on said head towards and away from the spindle of the other wheel to move the wheels together into grinding relation or separate them, a bearing on said head, a driving pulley mounted on said bearing, and a pin and slot connection between said pulley and the associated spindle and by which the spindle is turned by the pulley but an axial movement of the spindle independently of the pulley may be effected.

11. In a combined grinding and dressing machine, the combination of two spindles arranged end to end but out of axial alignment, a grinding wheel carried by each spindle and between which the article may be received and ground by said wheels arranged one eccentrically of the other, means for mounting said spindles with the wheels thereon for relative axial sliding movement toward and away from each other, and an interponent movable into and out of co-operative relation with a part that moves axially with one of said spindles and is adapted to arrest the axial movement thereof, said interponent when moved out of co-operative relation permitting the wheels to bear one against the other to dress the wheels.

12. In a combined grinding and dressing machine, the combination of two spindles arranged end to end but out of axial alignment, a grinding wheel carried by each spindle and between which the article may be received and ground by said wheels arranged one eccentrically of the other, a bearing member supporting one of said

spindles and mounted for axial sliding movement with its spindle towards and away from the spindle of the other wheel, an interponent movable into and out of co-operative relation with a part carried by 70 said bearing member and adapted to arrest the latter in its axial movement, and means for effecting an adjustment of said part to different set positions on said bearing member.

13. In a combined grinding and dressing machine, the combination of two spindles arranged end to end, a grinding wheel carried by each spindle and between which wheels the article may be received and 80 ground by said wheels, a bearing member supporting one of said spindles and mounted for axial sliding movement with its spindle, a part carried by and adjustable to different set positions on said bearing member, and an interponent movable into and out of co-operative relation with said adjustable part and adapted to co-act therewith to arrest the bearing member in its axial movement, said interponent when 90 moved out of co-operative relation permitting the wheels to bear one against the other to dress the wheels.

14. In a combined grinding and dressing machine, the combination of two spindles arranged end to end, a grinding wheel carried by each spindle and between which wheels the article may be received and ground, a hollow oil containing bearing member supporting one of said spindles in a bath of oil 100 and mounted for axial sliding movement with its spindle towards and away from the spindle of the other wheel to move the wheels together in grinding relation or separate them, a part carried by said bearing member, an interponent movable into and out of co-operative relation with said part and adapted to co-act therewith to arrest the axial movement of said bearing member and the parts carried thereby, and means for 110 affording an adjustment of said part to different set positions on said bearing member.

15. In a combined grinding and dressing machine, the combination of two spindles arranged end to end, a grinding wheel carried by each spindle and between which wheels the article may be received and ground, a bed, a head adjustable along said bed, a bearing member supporting one of said spindles and freely mounted for axial sliding movement with its spindle on said head towards and away from the spindle of the other wheel to move said wheels together into grinding relation or to separate them, and an interponent movable into and out of operative position and adapted to arrest said bearing member and the parts carried thereby in their axial movement or leave them free from arrest by said inter- 120 125 130

ponent so that one wheel may coact with the other to dress the wheels.

16. In a combined grinding and dressing machine, the combination of two spindles arranged end to end, a grinding wheel carried by each spindle and between which wheels the article may be received and ground, a bed, a head adjustable along said bed, a bearing member supporting one of said spindles and mounted for axial sliding movement with its spindle on said head towards and away from the spindle of the other wheel to move said wheels together into grinding relation or to separate them, a bearing fixed on said head, a driving pulley mounted on said bearing, and a pin and slot connection between said pulley and the associated spindle by which the spindle is turned by the pulley but an axial movement of the spindle independently of the pulley may be effected.

17. In a grinding machine, the combination of a pair of oppositely disposed grinding wheels between which an article is received and by which the article is simultaneously ground on opposite faces, means for effecting a relative axial movement between the grinding wheels to cause them to coact with the article to be ground, and means for supporting the article to be ground, said last mentioned means comprising an automatically actuated pivoted arm, a holder to which the article to be ground may be secured, and intermediate connections between said holder and arm that enable said holder to move to different parallel planes and to different angular positions relative to said planes but which prevent the holder from moving lengthwise of said arm, a pivotal movement of said arm moving the article to be ground towards and from the axes of said wheels.

18. In a grinding machine, the combination of a pair of oppositely disposed grinding wheels between which an article is received and by which the article is simultaneously ground on opposite faces, and means for supporting the article to be ground, said means comprising a pivoted arm, a holder to which the article to be ground may be secured, and intermediate connections between said holder and arm that include a plurality of pivoted supporting members, the pivotal axes of which are in planes at substantially right angles one to another.

19. In a grinding machine, the combination of a pair of oppositely disposed grinding wheels between which an article is received and by which the article is ground on opposite faces, and means for supporting the article to be ground, said means comprising a pivoted arm, a holder to which the article to be ground may be secured,

and intermediate connections between said holder and arm including a support pivotally connected to said arm and having its pivotal axis extending at substantially right angles to said arm, a second support pivoted on said first mentioned support and having its pivotal axis substantially parallel with that of the first support, and a third support which carries the holder and has its pivotal axis at substantially right angles to that of the second support.

20. In a grinding machine, the combination of a pair of oppositely disposed grinding wheels between which an article is received and by which the article is ground on opposite faces, and means for supporting the article to be ground, said means comprising a pivoted arm, a holder to which the article to be ground may be secured, and intermediate connections between said holder and arm that enable the holder to receive a limited unrestrained movement laterally of the arm and at different angles thereto so that the article on the holder is positioned in parallelism with the grinding faces of the wheels by said contact of the grinding faces therewith.

21. In a grinding machine the combination of a pair of oppositely disposed grinding wheels mounted on substantially horizontally disposed spindles, and means for supporting the article to be ground between said wheels, said means comprising an arm pivoted to turn on a substantially horizontally disposed axis, a support pivotally connected with said arm to turn on a substantially horizontally disposed axis, a second support pivoted to the first mentioned support to turn on a substantially horizontally disposed axis, and a third support which carries the holder and is pivoted to the second support to turn on a substantially vertically disposed axis.

22. In a grinding machine, the combination of a pair of oppositely disposed grinding wheels mounted on parallel axes and between which the article to be ground is received and ground on opposite sides, and automatically operating means by which the article is introduced between said wheels; by which a relative movement of the wheels towards each other is effected to cause them to bear against the article; by which the article is moved back and forth during the grinding operation; by which the wheels are moved relatively away from each other after the grinding operation is completed; and by which the ground article is withdrawn from between the wheels.

23. In a grinding machine, the combination of a pair of oppositely disposed grinding wheels between which the article to be ground is received and ground on opposite sides, automatically operating means by

which the article is introduced between said wheels; by which a relative movement of the wheels towards each other is effected to cause them to bear against the article; 5 by which the article is moved back and forth during the grinding operation; by which the wheels are moved relatively away from each other after the grinding operation is completed; and by which the ground 10 article is withdrawn from between the wheels, and automatically operating means for throwing said first mentioned automatically operating means out of action after the above described cycle of operations has 15 been effected.

24. In a grinding machine, the combination of a grinding wheel, means for moving said wheel against the article to be ground and which includes a positively actuated 20 member and a resilient member through which said movement is transmitted to the wheel from said positively actuated member, and a stop to positively arrest the said movement of the wheel under the action of 25 the resilient member.

25. In a grinding machine, the combination of a pair of grinding wheels, means for effecting a relative movement between said wheels to bring about a contact thereof 30 with the article to be ground between them and which includes a positively actuated member and a resilient member through which said relative movement between the wheels is transmitted from said positively 35 actuated member, and adjustable means for positively arresting and limiting said relative movement of the wheels under the action of said resilient member.

26. In a grinding machine, the combination of a pair of grinding wheels, and automatically operating means for effecting relative forward and back movements between said wheels, said means including positively operating moving devices, and a resilient 45 member intermediate said moving devices and a part to be moved to effect the said relative movement of the wheels, the relative movement between the wheels in both directions being effected by said positively operating devices acting through said resilient member.

27. In a grinding machine, the combination of a pair of grinding wheels, automatically operating means for effecting relative forward and back movements between 55 wheels, said means including positively operating moving devices, and a resilient member intermediate said moving devices and a part to be moved to effect the said relative movement of the wheels and through which motion is transmitted from said positively operating devices, and an interponent movable into and out of operative position and when in the operative position adapted to

arrest the relative movement of said wheels 65 towards each other and when out of operative position permitting the face of one wheel to be dressed by the other.

28. In a grinding machine, the combination of a pair of grinding wheels, automatically operating means for effecting relative forward and back movements between said wheels, said means including positively operating moving devices, and a resilient member intermediate said moving devices 70 and a part to be moved to effect the said relative movement of the wheels and through which motion is transmitted from said positively operating devices, an interponent 75 movable into and out of operative position 80 and when in the operative position adapted to arrest the relative forward movement between said wheels, and when out of operative position permitting the face of one wheel to be dressed by the other, and relatively adjustable stop devices adapted to 85 arrest such relative movement of the wheels when the interponent is in the inoperative position.

29. In a grinding machine, the combination of a grinding wheel, automatically operating means for controlling the movement of an article into and out of co-operative relation with the grinding wheel and for controlling the movement of the wheel 90 against and away from the article, and automatically operating means for disconnecting the driving means for said first mentioned automatically operating means 95 after its cycle of operations has been completed.

30. In a grinding machine, the combination of a grinding wheel, automatically operating means for controlling the movement of an article into and out of co-operative relation with the grinding wheel and for controlling the movement of the wheel against and away from the article; and automatically operating means for disconnecting the driving means for said first mentioned automatically operating means after its cycle of operations has been completed, said automatic disconnect mechanism including means that enable two gears to be thrown out of mesh, means for supporting said gears in 105 mesh, and automatically operating means for releasing said supporting means.

31. In a grinding machine, the combination of a grinding wheel, automatically operating means for controlling the movement of an article into and out of co-operative relation with the grinding wheel and for controlling the movement of the wheel against and away from the article, automatically operating means for disconnecting 120 the driving means for said first mentioned automatically operating means after its cycle of operations has been completed, said auto- 125

matic disconnect mechanism including means that enable two gears to be thrown out of mesh, means for supporting said gears in mesh, an automatically operating means for releasing said supporting means, and hand actuated means operable at will to reestablish a meshing engagement between said gears.

32. In a combined grinding and dressing machine, the combination of two spindles arranged endwise of each other with their axes parallel, grinding wheels carried by said spindles and each with a grinding face that moves transversely across the grinding face of the other wheel as the wheels turn with their spindles and between which faces the article to be ground is received and supported, means for supporting said article between said wheels, said means being so arranged that it does not interfere with the bringing of the grinding wheels face to face when dressing thereof is to be done, and means for effecting a relative longitudinal sliding movement of said spindles at one time to bring the wheels in grinding relation with the article to be ground and also at another time to bring the grinding faces of the wheels together to dress them.

33. In a combined grinding and dressing machine, the combination of two spindles arranged endwise of each other with their axes parallel, grinding wheels carried by said spindles and each with a grinding face that moves transversely across the grinding face of the other wheel as the wheels turn with their spindles, means for effecting a relative longitudinal sliding movement of said spindles to bring the grinding faces of the wheels together to dress them, and an interponent movable into and out of operative position and effect an arrest of said relative movement of the spindles when the interponent is in the operative position, thus enabling the wheels to grind to a given depth an article interposed between them and allow the grinding faces to operate one on the other when the interponent is moved to inoperative position.

34. In a grinding machine, the combination of two spindles arranged endwise of each other, grinding wheels carried by said spindles and operative on opposite sides of the interposed article to be ground, means for mounting said spindles for relative longitudinal movement to move the wheels relatively towards and away from each other, a holder for the article to be ground, a cam shaft, and means controlled thereby for moving the work holder to introduce the article between the wheels; for effecting a relative longitudinal movement of the spindles to bring the wheels to bear on the article; for oscillating the work holder while the article is being ground; for shifting the spindles

spindles longitudinally to effect a relative movement of the wheels away from each other and for moving the work holder to withdraw the article from between said wheels.

35. In a grinding machine, the combination of two spindles arranged endwise of each other, grinding wheels carried by said spindles and operative on opposite sides of the interposed article to be ground, means for mounting said spindles for relative longitudinal movement to move the wheels relatively towards and away from each other, a holder for the article to be ground, a cam shaft, means controlled thereby moving the work holder to introduce the article between the wheels; for effecting a relative longitudinal movement of the spindles to bring the wheels to bear on the article; for oscillating the work holder while the article is being ground; for shifting the spindles longitudinally to effect a relative movement of the wheels away from each other and for moving the work holder to withdraw the article from between said wheels, and automatically operating means for throwing said cam shaft out of operation after the foregoing cycle of operations has been completed.

36. In a grinding machine, the combination of two spindles arranged endwise of each other, grinding wheels carried by said spindles and operative on opposite sides of the interposed article to be ground, means for mounting said spindles for relative longitudinal movement to move the wheels relatively toward and away from each other, a holder for the article to be ground, a cam shaft, means controlled thereby for moving the work holder to introduce the article between the wheels; for effecting a relative longitudinal movement of the spindles to bring the wheels to bear on the article; for oscillating the work holder while the article is being ground, for shifting the spindles longitudinally to effect a relative movement of the wheels away from each other and for moving the work holder to withdraw the article from between said wheels, driving means for said cam shaft, automatically operating means for disconnecting said driving means from the cam shaft, and hand controlled means operable at will for re-connecting said driving means to the cam shaft.

37. In a grinding machine, the combination of spindles arranged endwise of each other, oppositely disposed cup-shaped grinding wheels mounted on said spindles, means for mounting said spindles to receive a relative longitudinal movement to bring the wheels together or separate them, an axially disposed passage for fluid through at least one of said spindles and its wheel, means for supplying fluid through said passage to the

grinding wheels, and automatically operated means for controlling the supply of fluid through said passage.

38. In a grinding machine, the combination of oppositely disposed relatively movable grinding wheels between which the article to be ground is received and by which it is simultaneously ground on opposite side faces, and a floating work holding element free from lateral restraint for holding the article between said wheels, the plane of the article between the wheels being regulated by the pressure of the wheels thereon.

39. In a grinding machine, the combination of two grinding wheels operative on opposite sides or faces of the article to be ground, a floating holder to which the article to be ground may be secured and by which it may be brought and maintained between oppositely disposed grinding faces of said wheels, and automatically operating means for controlling the movement of the holder into operative position and for controlling the relation between said wheels.

40. In a grinding machine, the combination of two grinding wheels adapted to grind opposite faces of the interposed article to be ground, a floating holder to which the article may be secured and by which it may be brought and maintained between oppositely disposed grinding faces on said wheels, means for mounting said holder so that it has a controlled movement towards and from the axes of said wheels and also a limited uncontrolled movement longitudinally of said axes and at different angles thereto but is restrained against turning movement with said wheels, and automatically operating means for moving said holder into and out of operative position and for controlling the relation between said wheels.

41. In a grinding machine, the combination of two grinding wheels adapted to grind opposite faces of the interposed article to be ground, a floating holder to which the article may be secured and by which it may be brought and maintained between oppositely disposed grinding faces on said wheels, means for mounting said holder to turn on axes at substantially right angles one to another so that the article may be held restrained against movement between said wheels in certain directions but has limited uncontrolled movements between said wheels in other directions, and automatically operating means for moving said holder into and out of operative position and for moving it back and forth while in operative position and for controlling the relation between said wheels.

42. In a grinding machine, the combination of two grinding wheels having oppositely disposed parallel grinding faces by which an interposed article may be ground on opposite parallel sides, a holder to which

the article may be secured and by which the article may be introduced and maintained between the grinding faces of said wheels, means for supporting said holder so that it has a limited freedom of movement in certain directions controlled or restrained only by the parallel grinding faces of the wheels on the article, thus enabling the article to automatically find its position parallel to the grinding faces wholly by the pressure of the grinding faces thereon, automatically operating means for moving said supporting means to control the movement of the holder into and out of operative position and for moving it back and forth while in the operative position, and automatically operating means for controlling the relation between said wheels and the relative movement thereof into and out of grinding position.

43. In a grinding machine, the combination of two spindles arranged end to end, a grinding wheel carried by each spindle and between which the article may be received and ground on opposite sides, a hollow oil containing bearing member supporting one of said spindles in a bath of oil and mounted for axial movement with its spindle towards and away from the spindle of the other wheel to bring the wheels in grinding relation or separate them, a holder for the article to be ground, and automatically operating means for controlling the movements of said holder into and out of grinding position.

44. In a grinding machine, the combination of two spindles arranged end to end, a grinding wheel carried by each spindle and between which the article may be received and ground on opposite sides, a hollow oil containing bearing member supporting one of said spindles in a bath of oil and mounted for axial movement with its spindle towards and away from the spindle of the other wheel to bring the wheels in grinding relation or separate them, a holder for the article to be ground, automatically operating means for controlling the movements of said holder into and out of grinding position and for moving the holder back and forth while the article is being ground, and automatically operating means for controlling the axial movement of said bearing member.

45. In a grinding machine, the combination of two grinding wheels having oppositely disposed parallel grinding faces by which an interposed article may be ground on opposite parallel sides, a holder to which the article may be secured, automatically operating means by which said holder may be shifted to introduce and maintain the article to be ground between the parallel grinding faces of said wheels and which enable the holder to receive a limited unrestrained movement to enable the parallel sides of the article to assume various planes parallel to the grinding faces of said wheels

and also to assume planes at various angles thereto and thus accommodate themselves to the grinding faces of the wheels but which restrains the holder and article against movements in said planes, and automatically operating means for controlling relative axial movements between said wheels to bring them into grinding relation and to separate them.

46. In a grinding machine, the combination of grinding means; and work supporting means comprising a primary support movable to bring the work into and out of co-operative relation with said grinding means, a plurality of floating work holders carried thereby, and means which enable the work holders to be shifted relatively to said primary support so that one holder may replace another in operation.

47. In a grinding machine, the combination of grinding means; and work supporting means comprising a primary support movable to bring the work into and out of co-operative relation with said grinding means, a secondary support shiftable relatively to said primary support, means for locking the secondary support in the different positions to which it may be shifted relatively to said primary support, and a plurality of floating work holders carried by said secondary support.

48. In a grinding machine, the combination of grinding means; and work supporting means comprising a pivoted primary support, a secondary support pivoted on said primary support and shiftable on its pivot to different set positions, and a plurality of floating work holders pivotally supported on said secondary support.

49. In a grinding machine, the combination of grinding means; and work supporting means comprising a supporting member, a plurality of holders to each of which an article to be ground may be secured, and intermediate connections between said holders and said member that enable each holder to move to different parallel planes and to different angular positions relative to said planes but which prevent each holder from moving lengthwise of said member.

50. In a grinding machine, the combination of grinding means; work supporting means comprising a supporting member, a plurality of holders to each of which an article to be ground may be secured, and intermediate connections between said holders and said member that enable each holder to move to different parallel planes and to different angular positions relative to said planes but which prevent each holder from moving lengthwise of said member; and means which enable the plurality of holders to be shifted together relatively to said member so that one holder may replace another in operation.

51. In a grinding machine, the combination of grinding means; and work supporting means comprising a pivoted supporting arm, a plurality of holders to each of which an article to be ground may be secured, intermediate pivotal connections between said holders and said arm that enable each holder to move to different parallel planes and to different angular positions relative to said planes but which prevent each holder from moving lengthwise of said arm, and a pivotal connection that enables the plurality of holders to turn together on said arm so that one holder may replace another in operation.

52. In a grinding machine, the combination of grinding means; and work supporting means comprising a pivoted arm, a plurality of holders to each of which an article to be ground may be secured, and intermediate connections between each holder and said arm including a support pivotally connected to said arm and having its pivotal axis extending at substantially right angles to said arm, a second support pivoted on said first mentioned support and having its pivotal axis substantially parallel with that of the first support, and a third support which carries the associated holder and has its pivotal axis at substantially right angles to that of the second support.

53. In a grinding machine, the combination of grinding means; and work supporting means comprising a pivoted arm, a plurality of holders to each of which an article to be ground may be secured, and intermediate connections between each holder and said arm including a support pivotally connected to said arm and having its pivotal axis extending at substantially right angles to said arm, a second support pivoted on said first mentioned support and having its pivotal axis substantially parallel with that of the first support, a third support which carries the associated holder and has its pivotal axis at substantially right angles to that of the second support, and means whereby all of said supports may be turned together on said arm to cause one holder to replace another.

54. In a grinding machine, the combination of a main supporting member, a head carried thereby, a link pivoted to said head, a support pivoted to said link, and a work holder pivoted to said support.

55. In a grinding machine, the combination of a main supporting member, a head carried thereby, a plurality of links pivoted to said head, a support pivoted to each link, and a work holder pivoted to each support.

56. In a grinding machine, the combination of a movable main supporting member, a head pivoted thereon to enable the head to be shifted or turned to different set positions, a plurality of links pivoted to said head, a support pivoted to each link, a work

holder pivoted to each support, and releasable locking means for said head to enable it to be locked in its set position on the main supporting member and to enable it to be shifted when desired to cause one holder to replace another.

57. In a grinding machine, the combination of a main supporting member, a head carried thereby, a link pivoted to said head, 10 a support pivoted to said link, a work holder pivoted to said support, and automatically operating means for controlling the movement of said main supporting member.

58. In a grinding machine, the combination of a movable main supporting member, 15 a head pivoted thereon to enable the head to be shifted or turned to different set positions, a plurality of links pivoted to said head, a support pivoted to each link, a work holder pivoted to each support, releasable locking means for said head to enable it to be locked in any of its set positions on the main supporting member and to enable it to be shifted when desired to cause one holder 20 to replace another, and automatically operating means for controlling the movement of said main supporting member.

59. In a grinding machine, the combination of a main supporting member, a head carried thereby, a link pivoted to and carried by said head, a support pivoted to and carried by said link, the pivotal axes of the link and support being parallel, and a work holder pivoted to and carried by said support, the pivotal axis of the work holder being at substantially right angles to the pivotal axis of said support.

60. In a grinding machine, the combination of grinding wheels, a work holder, and 40 means co-operating therewith to control and restrain its movements towards and from the axes of the wheels and in the direction of rotation of the wheels but to support the holder to move a limited distance free from 45 restraint in every other direction.

61. In a grinding machine, the combination of grinding wheels, a plurality of work holders, means co-operating with each work holder to control and restrain its movements 50 when in use towards and from the axes of the wheels and in the direction of rotation of the wheels but to support such holder to move a limited distance free from restraint in every other direction, and means which 55 enable said holders to be shifted to replace one by another in position for use.

62. In a grinding machine, the combination of a pair of grinding wheels, an arm pivoted on a substantially horizontal axis to 60 move an article to be ground into and out of position between said wheels, a head on said arm, a carrier pivoted at one end on said head on an axis that extends in a plane at substantially right angles to the axis of 65 said arm, a second carrier pivoted to the

other end of the first mentioned carrier on an axis parallel with the axis thereof, and a work holder pivoted to said second carrier on an axis that is at substantially right angles to the axis thereof.

70

63. In a grinding machine, the combination of a pair of grinding wheels, an arm pivoted on a substantially horizontal axis to move an article to be ground into and out of position between said wheels, a head on said arm, a carrier pivoted at one end on said head on an axis that extends in a plane at substantially right angles to the axis of said arm, a second carrier pivoted to the other end of the first mentioned carrier on an axis parallel with the axis thereof, a work holder pivoted to said second carrier on an axis that is at substantially right angles to the axis thereof, a second set of carriers and a work holder like those set forth carried by said head, and means which enable said head to be turned on said arm to replace one holder for another in position for use.

75

64. In a grinding machine, the combination of a pair of grinding wheels, an arm pivoted on a substantially horizontal axis to move an article to be ground into and out of position between said wheels, a head on said arm, a carrier pivoted at one end on said head on an axis that extends in a plane at substantially right angles to the axis of said arm, a second carrier pivoted to the other end of the first mentioned carrier on an axis parallel with the axis thereof, a work holder pivoted to said second carrier on an axis that is at substantially right angles to the axis thereof, a second set of carriers, and a work holder like those set forth carried by said head, means which enable said head to be turned on said arm to replace one holder for another in position for use, automatically operating means for moving said arm, and automatically operating means for effecting a relative movement of said wheels into and out of grinding relation.

80

65. In a grinding machine, the combination of oppositely disposed grinding wheels between which the article to be ground is received, a floating work holding element free from lateral restraint for a limited extent, and automatically operating means for moving the work holder into and out of working position and for effecting a relative movement of the wheels into and out of grinding position and for throwing the machine out of operation after it has completed a cycle of movements.

85

66. In a grinding machine, the combination of grinding means; work supporting means comprising a primary support movable to bring the work into and out of co-operative relation with said grinding means, a plurality of floating work holders carried thereby, and means which enable the work holders to be shifted relatively to said pri-

mary support so that one holder may replace another in operation; and automatically operating means for moving the primary support.

- 5 67. In a grinding machine, the combination of grinding means, work supporting means comprising a primary support movable to bring the work into and out of co-operative relation with said grinding means, 10 a secondary support shiftable relatively to said primary support, means for locking the secondary support in the different positions to which it may be shifted relatively to said primary support, and a plurality of 15 floating work holders carried by said secondary support; automatically operating means for moving said primary support; and automatically operating means for bringing the grinding means into grinding 20 relation with an article to be ground.

68. In a grinding machine, the combination of grinding means; work supporting means comprising a supporting member, a plurality of holders to each of which an article to be ground may be secured, intermediate connections between said holders and said member that enable each holder to move to different parallel planes and to different angular positions relative to said 30 planes but which prevent each holder from moving lengthwise of said member, and means which enable the plurality of holders to be shifted together relatively to said member so that one holder may replace another in operation; automatically operating means for moving said supporting member to move an article to be ground into and out of co-operative relation with said grinding means; automatically operating means for moving the grinding means into and out of grinding position; and automatically operating means for throwing the machine out of operation after it has completed a cycle of movements.

69. In a grinding machine, the combination of grinding means; work supporting means comprising a pivoted supporting arm, a plurality of holders to each of which an article to be ground may be secured, intermediate pivotal connections between said holders and said arm that enable each holder to move to different parallel planes and to different angular positions relative to said planes but which prevent each holder from moving lengthwise of said arm, and a pivotal connection that enables the plurality of holders to turn together on said arm so that one holder may replace another in operation; and automatically operating means for moving said pivoted supporting arm.

70. In a grinding machine, the combination of grinding means; work supporting means comprising a pivoted supporting arm, a plurality of holders to each of which an article to be ground may be secured, inter-

mediate pivotal connections between said holders and said arm that enable each holder to move to different parallel planes and to different angular positions relative to said planes but which prevent each holder from moving lengthwise of said arm, and a pivotal connection that enables the plurality of holders to turn together on said arm so that one holder may replace another in operation; automatically operating means for controlling said supporting arm and the grinding means to automatically introduce grind and withdraw an article; and automatically operating means for throwing the machine out of operation after an article has been withdrawn.

71. In a grinding machine, the combination of a movable main supporting member a head pivoted thereon to enable the head to be shifted or turned to different set positions, a plurality of links pivoted to said head, a support pivoted to each link, a work holder pivoted to each support, releasable locking means for said head to enable it to be locked in its set position on the main supporting member and to enable it to be shifted when desired to cause one holder to replace another, automatically operating means for controlling said main supporting member to introduce an article to be ground and withdraw it after being ground, and automatically operating means for moving said grinding means into and out of grinding relation.

72. In a grinding machine, the combination of grinding wheels, a work holder, and means co-operating therewith to control and restrain its movements towards and from the axes of the wheels and in the direction of rotation of the wheels but to support the holder to move a limited distance free from restraint in every other direction, said means including automatically operating means for moving the work holder to introduce an article to be ground and withdraw it after being ground.

73. In a grinding machine, the combination of grinding wheels; a plurality of work holders; means co-operating with each work holder to control and restrain its movements when in use towards and from the axes of the wheels and in the direction of rotation of the wheels but to support such holder to move a limited distance free from restraint in every other direction, said means including automatically operating means for moving said work holder to introduce an article to be ground and withdraw it after being ground; automatically operating means for effecting a relative movement between said wheels into and out of grinding position; and means which enable said holders to be shifted to replace one by another in position for use.

74. In a grinding machine, the combina-

tion of grinding wheels; a plurality of work holders; means cooperating with each work holder to control and restrain its movements when in use towards and from the axes of the wheels and in the direction of rotation of the wheels but to support such holder to move a limited distance free from restraint in every other direction, said means including automatically operating means for moving said work holder to introduce an article to be ground to move the article back and forth under the grinding operation and to withdraw the article after it is ground; automatically operating means for effecting a relative movement of said wheels into and out of grinding position; automatically operating means for throwing the machine out of operation after it has completed a cycle of movements; and means which enable said holders to be shifted to replace one by another in position for use.

75. In a grinding machine, the combination of a pair of oppositely disposed grinding wheels between which an article to be ground is received, and means for automatically effecting a relative movement between said wheels into and out of grinding relation, said means including a power driven positively actuated member and resilient means through which said relative movement of the wheels is transmitted from said positively actuated member.

76. In a grinding machine, the combination of grinding means; a work holder; and means for detachably securing the article to be ground to the work holder, said means comprising a locking member mounted for movement into and out of locking position, and a lever-like member for controlling such movements of the locking member.

77. In a grinding machine, the combination of grinding means; a work holder; and means for detachably securing the article to be ground to the work holder, said means comprising a locking member mounted for sliding movement into and out of locking position, and a controlling member pivotally connected to said locking member for controlling the sliding movement of the latter.

78. In a grinding machine, the combination of grinding means; a work holder; and means for securing the article to be ground to the work holder, said means comprising a clamping member movable on the work holder, a spring, and means for controlling the action of said spring to exert its force on the clamping member and the article to be held thereby and to release the force of the spring on said member and enable the article to be removed from the holder.

79. In a grinding machine, the combination of grinding means; a work holder; and means for securing the article to be ground to the work holder, said means comprising

a clamping member movable on the work holder, a spring, and means for controlling the action of said spring to exert its force on the clamping member and the article to be held thereby and to release the force of the spring on said member and enable the article to be removed from the holder, said controlling means including means whereby it is retained against accidental displacement from the position where it is effective to apply the force of the spring to said clamping member and the article held thereby.

80. In a grinding machine, the combination of grinding means; a work holder; and means for detachably securing the article to be ground to the work holder, said means comprising a locking member mounted for sliding movement into and out of co-operative relation with the article to be ground and effective to retain it in place, and a controlling member mounted on said locking member to receive pivotal movement thereon, a pivotal movement of said controlling member in one direction effecting a sliding movement of the locking member to engaging position, and a pivotal movement of the controlling member in the opposite direction permitting a sliding movement of the locking member to releasing position.

81. In a grinding machine, the combination of grinding means; a work holder; and means for detachably securing the article to be ground to the work holder, said means comprising a locking member mounted for sliding movement into and out of engagement with the article to be ground and effective to retain it in place, a controlling member having a cam and mounted on said locking member to move relatively thereto, such relative movement of said controlling member controlling the action of said cam and the movement of the locking member into engaging position, and a spring which is flexed by said cam and exerts its force through said locking member on the article to be ground to hold the latter in place.

82. In a grinding machine, the combination of grinding means; a work holder having a seat in which the article to be ground may be seated; and means for detachably securing the article in said seat, said means comprising a locking member mounted on the work holder for movement into and out of engagement with the article contained in said seat, a spring, and means for applying and releasing the force of said spring on said locking member and on the article with which it coacts.

83. In a grinding machine, the combination of grinding means; a work holder having a seat in which the article to be ground may be seated; and means for detachably securing the article in said seat, said means comprising a locking member mounted on said holder for independent movement there-

on, the independent movements of said member carrying a contact thereon into and out of engagement with the article contained in said seat, a spring, and a controlling member pivotally mounted on said locking member and having a cam which is rendered effective by a pivotal movement of the controlling member to apply or release the force of said spring on said locking member.

Signed at Ilion, in the county of Herkimer and State of New York, this 14th day of September A. D. 1921.

WILHELM A. SCHMIDT.
